UNITED STATES PATENT OFFICE.

ELMER D. MANKEDICK, OF INDIANAPOLIS, INDIANA.

WALL CONSTRUCTION.

Application filed October 12, 1925. Serial No. 62,134.

This invention pertains to wall construction and has for an object the provision of building members of a construction such that they may be assembled to form a composite wall for use in the erection of buildings, sea walls, etc.

Another object of the invention is to provide members which interengage and interlock to provide a water and air tight wall not subject to deterioration and capable of withstanding any reasonable strain imposed thereon.

Other objects of the invention will be apparent from the following description of the present form of the invention taken in connection with the accompanying drawings wherein:—

Fig. 1 is a fragmentary side elevational view of a wall constructed in accordance with the present invention;

Fig. 2 is a top plan view of the same, part thereof being broken away to disclose details;

Fig. 3 is a sectional view taken on the line 3—3' of Fig. 1 looking in the direction of the arrow;

Fig. 4 is a fragmentary side elevational view of the wall showing the manner of mounting a window therein;

Fig. 5 is a horizontal sectional view thereof taken on the line 5—5 of Fig. 4 looking in the direction of the arrows;

Fig. 6 is a vertical sectional view of a wall assemblage as shown in Fig. 1;

Fig. 7 is a detail fragmentary perspective view of one of the wall caps;

Fig. 8 is a similar view of one of the corner posts;

Fig. 9 is a detail fragmentary perspective view of one of the intermediate posts;

Fig. 10 is a similar view of one of the wall slabs;

Fig. 11 is a similar view of one of the bottom sills;

Fig. 12 is a vertical sectional view taken on the line 12—12 of Fig. 4 looking in the direction of the arrow;

Fig. 13 is a detail fragmentary perspective view of the window casing; and

Fig. 14 is a detail fragmentary perspective view of a bottom sill used in the construction of the window casing.

A wall constructed in accordance with the present invention embodies a base 15 preferably made of plastic material which may be partially or wholly embedded in the

ground in order to provide a support for the wall structure which is supported thereby, preferably along the longitudinal axis of the base and in spaced relation to the opposite sides of the latter, as illustrated in Fig. 6.

Upstanding on the base 6, at predetermined intervals, are a series of intermediate posts 16 each of which, as shown to advantage in Fig. 9, is rectangular in cross section and is provided with longitudinally extending grooves 17 in the opposite sides thereof. Each of the posts is provided with a central longitudinally extending core 18 which, in the present instance, consists of a metal rod the ends of which project beyond the upper and lower ends of the posts. The lower end of the core 18 is embedded in the base 15 as shown in Fig. 1. In addition to the intermediate posts, corner posts 19 are provided wherever necessary, each being provided with longitudinally extending grooves 20 in two adjacent sides thereof, the corner posts being also provided with cores 18.

Mounted on the base 15 between each pair of posts is a bottom sill 21 the terminals of which are reduced to provide tongues 22 which fit in the lower ends of the grooves 17 and 20 of the intermediate and corner posts respectively or in the grooves of relatively adjacent ones of the intermediate posts, depending upon the location of the sills. The top of the sill is provided midway its sides with an upstanding rib 23 one side of which is disposed at an inclination and the other side vertically disposed as shown in Fig. 6. This rib fits in a complementary groove 24 formed in the bottom margin of a slab 25. Any number of slabs may be provided each of which is of rectangular form and provided on its upper edge with a rib 26 which is identical in cross sectional configuration and dimensions with the rib 23 but has its front face flush with the front face of the slab. The ends of the slabs 25 are fitted in the grooves 17 and 20 of the intermediate and corner posts or in the grooves of relatively adjacent ones of the intermediate posts, depending upon the location of the slabs while the upper and lower edges of mutually superposed slabs interfit to provide an air and water tight wall, as illustrated to advantage in Fig. 6.

The slabs are assembled in tiers and the rib on the uppermost slab of each tier fits into

a complementary groove formed in the under-side of a cap member 27. Each of the caps 27 has its ends rabbeted and arranged in overlapped relation with the terminals of adjacent caps so that the overlapped ends of the caps are of the same thickness as the bodies of the caps. The rabbeted ends of the caps are provided with openings 28 which receive the upper ends of the cores 18, said cores being projected appreciably above the upper face of the cap to engage superimposed portions of the wall or to be used as anchors for the roof where the wall is used in a building.

15 Preferably, the grooves 17 and 20 are of a width greater than the thickness of the slabs 25 and of a depth exceeding the length thereof so that the ends of the latter will freely enter the grooves and after having 20 been positioned therein in the proper manner may be permanently set by depositing a plastic material, such as mortar, 29 in the grooves. In this way, not only is assemblage 25 of the wall facilitated but moreover relative movement of the slabs or movement of the slabs relative to the posts will be eliminated.

Where it is desired to provide windows in the wall, a sill 30 is used as the bottom of the window casing and is similar to the 30 bottom sill 21 except that it is provided in its under side with a groove to accommodate the rib 26 upon the upper edge of the slab upon which it rests and may be ornamented on the top in any desired manner. The rib 35 on the upper face of the sill fits in a corresponding groove formed in the bottom of the window casing 31. The sides of the window casing are provided with ribs 32 which engage in the grooves 17 of the intermediate 40 posts between which the casing is located while the top of the window casing is provided with a rib 33 which fits in the groove in the under side of the cap 27 as shown in Fig. 12. Window sashes 34 are shown as 45 hingedly mounted in the window casing. It is, of course, understood that any number of windows or doors may be provided in precisely the same manner.

It is, of course, to be understood that the 50 wall may be of any desired height and thick-

ness and may be constructed of any material, but it is preferable to employ a plastic composition because of its cheapness to manufacture, durability, etc. It is apparent that building elements constructed in accordance with this invention may be quickly assembled to provide an air and water tight wall.

Various changes may be made in the details of construction, proportion and arrangement of parts within the scope of the claims 60 hereto appended.

What is claimed is:—

1. In wall construction, a sill member having an upstanding rib upon its upper side extending longitudinally thereof and spaced with respect to the planes of the front and rear faces of the member, and a slab having a groove in its lower edge receiving the said rib, the groove having angularly disposed walls, the slab being provided upon its upper edge with a longitudinal rib of the same contour as the groove to fit into the groove of a companion slab disposed above the first mentioned slab, the rib of the slab having a vertical face and a face inclined toward 75 and meeting one face of the slab.

2. In wall construction, a base of plastic material, spaced posts disposed at their lower ends upon the upper side of the base, a core extending longitudinally centrally within each post and projecting at its upper and lower ends beyond the upper and lower ends of the posts, the projecting lower ends of the cores being embedded in the base, a sill disposed upon the base and having interlocking engagement at its ends with the posts and extending between the said posts, slabs arranged one above another between the posts and having interlocking engagement at their ends with the said posts, the lower-most slab resting upon the sill, a cap to engage the upper ends of the posts and the upper edges of the uppermost slabs, the ends of relatively adjacent ones of the caps being rabbeted and overlapped above the upper ends of the posts and having openings accommodating the projecting upper ends of the cores.

In testimony whereof I affix my signature.

ELMER D. MANKEDICK.
